(57) **CLAIM**

The ornamental design for a camera mounted virtual reality sensor, as shown and described.

DESCRIPTION

FIG. 1 is a perspective view of the first embodiment the camera mounted virtual reality sensor showing my new design;

FIG. 2 is a top plan view thereof;

FIG. 3 is a front elevational view thereof wherein the rear elevational view is a mirror image of FIG. 3;

FIG. 4 is a perspective view of the second embodiment of the camera mounted virtual reality sensor showing my new design;

FIG. 5 is a top plan view thereof; and,

FIG. 6 is a front elevational view thereof wherein the rear elevational view is a mirror image of FIG. 6.

The broken lines shown in the figures are included for the purpose of illustrating the environment and form no part of the claimed design.
